UNITED STATES PATENT OFFICE.

MARTIN L. EDWARDS AND GEORGE M. SMITH, OF SALEM, OHIO; SAID SMITH ASSIGNOR TO SAID EDWARDS.

TYUERE.

SPECIFICATION forming part of Letters Patent No. 249,912, dated November 22, 1881.

Application filed September 8, 1880. Renewed May 11, 1881. (No model.)

To all whom it may concern:

Be it known that we, MARTIN LUTHER EDWARDS and GEORGE MILTON SMITH, citizens of the United States, residing at Salem, in the county of Columbiana and State of Ohio, have invented new and useful Improvements in Tuyeres, of which the following is a specification.

Our invention relates to tuyeres for blacksmiths' forges in which a blast-regulating valve and an ash-discharging valve are used and operated by separate levers; and the objects of our invention are to provide a cheap, simple, and effective means for operating the blast-regulating valve, and also to provide means for effectually removing the cinders and clinkers from the ash-discharge and its valve without the use of pokers. We attain these objects by the construction hereinafter described, and illustrated in the accompanying drawings, in which—

Figure 1 is a view in perspective, and Fig. 2 represents a vertical section through a tuyere embracing our invention; Fig. 3, a section on the line $x x$, Fig. 2; Fig. 4, a top view with the crown-plate removed; Fig. 5, a horizontal section, taken on the line $y y$ of Fig. 3 and looking down upon the discharge-valve of the basin, and Fig. 6 the scraper.

The bed-plate A in the forge-wall is of metal, preferably cast-iron, and is cast with its dependent basin, blast, or ash chamber B, as is now used in many cases, the projecting bed-plate or broad flange supporting the entire tuyere upon the bed. The bottom of this ash-chamber B has three triangular openings, $a a a$, to permit the ready escape of ashes and cinders. Through the imperforate central part of this bottom there is a screw-hole for the reception of a pivot-screw, b , which carries an under series of wings, c , composing a rotary valve for closing said basin-openings a , and which is operated by a lever, C, bringing the wings in position to cover the openings a or to leave them open or partially open, as desired. Stops e upon the outer bottom of the basin arrest the play of the valve-lever at points of full opening and full closing. This valve permits the escape of the deposits of ashes and cinders

when open, and when closed the entire blast 50 is directed to the top orifice.

On the upper side of the bottom of the ash-pit B, and attached to the rotating valve by means of the pivot-screw b , above described, there are equidistant armed scrapers fff , and 55 being so attached, when the valve is moved to bring its openings opposite those in the basin the arms of the scrapers are brought to the edges of the said basin-openings, thus removing all ashes, cinders, or clinkers from the basin, which arrangement of oscillating cutting-arms is of great importance and a valuable feature of our invention, for when ashes or other deposits are not removed the blast is obstructed and those parts of the tuyere exposed to the 65 fire are burned away.

Under the bed-plate A, at its junction with the dependent basin B and piercing said basin, are two opposite openings, $g g$, for the reception of a pushing valve-rod, D, projecting 70 from the tuyere at a sufficient distance to come just outside the forge, where it is operated to regulate at will an oval or hemispherical swinging valve, E, which latter is attached by a swing-yoke, $h h$, in seat-holes $i i$ in the upper 75 junction of the basin with the bed-plate, (although other means might be used,) the said swing-yoke being supported so as to drop the valve at right angles upon an incline, k , of the push-rod, so that when the valve push-rod is 80 operated by pushing it endwise through the openings $g g$ the ball-valve or globe-valve E is raised up into or lowered out of (in any desired gradation) the orifice l in the crown F of the tuyere, regulating the blast to various kinds 85 of work, as is well understood.

On the bottom of the tuyere-crown, near the orifice, are two projections, $m m$, which pass each side of the swing-yoke h near its middle, serving as guides for the valve E, causing it 90 to move up and down positively to the orifice, thereby regulating the blast. The swing-yoke arm h may be provided with an oblong opening or slot near its middle, engaging with but one projection, extending through the slot. 95 Ears o at the edge of the crown keep it in proper position, and the crown is made removable.

The push-rod, by reason of its seat-holes, may pass in from either right or left hand, the action of the incline on the rod being the same.

The advantages of our improvement in the 5 manner of closing or regulating the valve are apparent and are the result of our construction.

The bottom oscillating valve, operating in connection with a perforated bottom of the basin, is not new as applied to tuyeres, and we 10 do not claim these parts; but the scraper combined therewith is new and produces a new result in tuyeres—viz., the scraping out thoroughly of the deposits of the ash-pit.

15 The blast-pipe K is made of longitudinal sections, the lower one of which is integral with the bed-plate, and the upper section is joined therewith and with a semi-cylindrical extension, s, from the crown-plate, which is a 20 separate casting, screwed to the bed-plate, so as to be renewed when necessary.

The fire can be kept alive when the workman stops or is called away for a while by opening the bottom valve. It is important, also, to 25 notice that the means for regulating the blast are arranged above and at all times free from the accumulating cinders in the basin.

The valve and its operating-rod are of separate and distinct parts, and their arrangement and relation to each other are such that 30 they can be removed and replaced by others by removing the crown-plate. Should one become warped, such warping will not affect the proper adjustment of the valve in relation to the blast-orifice. The support for the valve is 35 central therewith, and its adjustment, while being vertical, is effected by the sliding action of an incline, upon which the valve rests, and as such sliding action of the incline is at right

40 angles to the adjustment of the valve, the latter is supported without danger of being pressed

down from above or of being moved when the desired adjustment is made.

It is not necessary that the oscillating scraper be secured to and operated by the bottom valve, 45 as they may be operated separately; but the scraper must operate upon the inner surface of the perforated bottom of the basin, and in such relation to such perforations as to clear the accumulations.

We claim—

1. In a tuyere, in combination with the ash-discharge, the armed scraper operated by the valve-lever C, substantially as and for the purpose described.

2. In a tuyere, the combination, with the regulating-valve swung in the basin, of the push-rod provided with an incline for supporting, raising, and lowering said valve, substantially as described.

3. In a tuyere, a regulating-valve swung by a yoke from the basin, as described, in combination with a push-rod provided with an incline and passing through holes in the basin, and guide-projections m from the under side 65 of the crown, substantially as described.

4. The combination of the oscillating ash-discharging valve, arranged on the under side of the perforated bottom of the basin, with an oscillating scraper, arranged upon the upper 70 side of said perforated bottom and operating to effect the discharge of the ashes when said valve is open, substantially as specified.

In testimony whereof we have hereunto set our hands in the presence of two subscribing 75 witnesses.

MARTIN LUTHER EDWARDS.
GEORGE MILTON SMITH.
